Primary Examiner — Cathy Anna MacCormac(74) *Attorney, Agent, or Firm* — Klintworth & Rozenblat IP LLP; Bruce L. Adams, Esq.(57) **CLAIM**

The ornamental design for a printer mechanism, as shown and described.

DESCRIPTION

FIG. 1 is a front and left side perspective view of a printer mechanism showing our new design;

FIG. 2 is a rear and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict environmental subject matter and form no part of the claimed design.

1 Claim, 7 Drawing Sheets(56)
